[57] ABSTRACT

A pedestal support for furniture comprising first and second support members affixed to opposite sides of a third support member, intermediate the ends thereof, forming a cross member. A post having longitudinal slots in one end is placed over the cross member received in the slots, and is then welded to the cross member, the weld filling the void between the cross member and the post.

FIG. 1

FIG. 2

FIG. 3

FIG. 4

FURNITURE SUPPORT

BACKGROUND OF THE INVENTION

This invention relates to supports for furniture and more particularly to a novel pedestal support for tables, chairs, racks, etc., as well as a novel method of fabricating the same.

Supports for furniture such as chairs, tables and the like are generally known in the prior art and are useful in numerous applications in industry, business and the home. For instance, supports have been constructed of a tubular post upon which a plurality of legs are radially placed and heavily welded after being properly cut and beveled. The weld is then sanded and polished to achieve a desired exterior appearance. Other like supports have been constructed in a similar manner; however, rather than sanding and polishing the resultant weld, a second tubular member is telescopingly placed over the tubular post to cover the weld. The second tubular member has no structural value, but merely serves to conceal the unsightly weld joints. These aforementioned pedestal supports are relatively costly to construct in view of the labor or parts required.

OBJECTS

Accordingly, it is a primary object of this invention to provide a novel pedestal support for furniture which will have sufficient strength and yet may be easily and economically manufactured in superior contrast to those of the prior art noted above. Included herein is such a furniture support which has fewer parts and may be manufactured to possess a pleasing appearance.

A further object of this invention is to provide such a furniture support which may be fabricated in various geometrical designs to suit various types of furniture or furniture designs.

A still further object of the present invention is to provide such a furniture support which will offer effective furniture support and will be durable over long periods of repeated and even rugged use.

SUMMARY OF INVENTION

The above objects are achieved in a furniture pedestal support which, in one embodiment, is comprised of two support members attached to opposite sides of a third member, intermediate the ends thereof, to form a base in the form of cross members. A post having longitudinal slots in one hollow end thereof, is placed over the cross members with the slots respectively receiving the cross members and concealing the welds therebetween. The post is then securely fixed to the cross members, such as by welding in the interior of the post so as to fill the voids therein between the post and the cross members.

DRAWINGS

Further details and other objects of this invention will become clear from the description and appended claims, appearing below, taken in conjunction with the accompanying drawings in which:

FIG. 1 is a perspective view of a table incorporating a pedestal support embodying the present invention, the table being illustrated in phantom lines;

FIG. 2 is a fragmental cross-sectional view taken along lines 2-2 of FIG. 1 showing the members of the support in subassembled, partly attached condition;

FIG. 3 is a view similar to FIG. 2 but with the support members in fully attached condition; and

FIG. 4 is an exploded perspective view of the support members illustrating assembly thereof.

DETAILED DESCRIPTION

Referring to the drawings in detail, there is shown in FIG. 1 for illustrative purposes only, a table generally designated T incorporating a support pedestal designated S embodying and made in accordance with, the present invention. Support pedestal S is attached to the underside of the table top T' in any suitable manner, so that when in use the pedestal supports the table top in a horizontal plane.

In the shown embodiment, the pedestal S includes support members 1 and 2 attached intermediate the ends of a third support member 3 on opposite sides thereof to form a cross configuration. In the specific embodiment shown, the support members 1, 2 and 3 are shown as elongated rectangular members having a rectangular cross section. It will be readily apparent that the support members may be made from any suitable material such as steel, aluminum or any suitable alloy. Also, other geometrical shapes may be employed in forming the support members 1, 2 and 3. Furthermore, although the secondary support members 1 and 2 are attached at right angles to the main support member 3, other angular relationships may be employed, such as wherein the support members 1 and 2 extend obliquely relative to the main support member 3. Since, in the shown embodiment, the support members 1, 2 and 3 have a rectangular shape, they are attached with each other so that the bottom surfaces in the lower support members all lie in the same plane. Similarly, with respect to the upper support members which are employed to secure the table top T', the upper surfaces of the support members all lie in the same plane to provide flush engagement with the underside of the table top. In the preferred embodiment, the support members 1, 2 and 3 are formed from a suitable material such as steel or aluminum, and they are attached to each other by means of welds designated 4 in FIG. 2.

After the support members 1, 2 and 3 are secured to each other in the aforementioned manner, an upright or post, shown in the form of a hollow tube, is secured to the support members at right angles to the plane of the support members. This is accomplished through the means of a plurality of elongated slots 6 formed in the ends of the post 5 to receive the base support members 1, 2 and 3, as shown in phantom lines in FIG. 4. The extent of the slots 6 corresponds to the depth of the support members 1, 2 and 3. Also, in view of the number and arrangement of support members, there are four equiangularly spaced slots provided in the ends of the post 5, as shown in FIG. 4. It will be apparent that once the post 5 is placed over the support members with the latter received in the slots 6, the welds 4 used to join the support members 1 and 2 to the main support member 3, will be enclosed in the post 5 to be concealed from view.

In order to complete the joint, the support members 1, 2 and 3 are fixed to the post 5 preferably by welds 7 placed within the end of the post 5 to completely fill the voids therein between the support members and the post, as shown in FIG. 3.

It will thus be seen that the present invention avoids the necessity of sanding and polishing welds to enhance

the appearance of the pedestal as is necessary with methods of the prior art. At the same time, the present invention avoids the necessity of applying a secondary tubular member to cover the welds. Furthermore, while providing the aforesaid advantages, the resulting pedestal of the present invention possesses sufficient strength and rigidity to provide effective support for furniture. Finally, it is noted that the aforementioned advantages are achieved with a minimum number of parts and labor and in accordance with a method which may be adapted to mass production with standard pieces of stock.

We claim:

1. A method of fabricating a support for an item of furniture such as a chair, table or the like comprising the steps of:

Rigidly attaching first and second support members to opposite sides of a third support member in transverse relation thereto;

Placing a post having a hollow lower end with slots 20 extending longitudinally therein, over said first, second and third support members with said support members received in said slots respectively and the post concealing the connection between the cross members and

Rigidly attaching said first, second and third support members to said post at said end thereof.

2. The method defined in claim 1 wherein the post is attached to said cross members by an agent located within said end of said post to be concealed from view.

3. The method defined in claim 1 wherein said first and second support members are attached to said third support member by a plurality of welds, and said first, second and third support members are attached to said 35 post by a plurality of welds located in said lower end of the post.

4. The method defined in claim 3 wherein said welds completely fill the void between said first, second and third support members and said post in said lower end 40 thereof.

5. A pedestal support for an item of furniture such as a chair, table or the like comprising:

a first base support member, 45
second and third base support members rigidly fixed to said first base support member and projecting outwardly from opposite sides thereof respectively,

an upright member having a hollow lower end with at least four slots extending longitudinally therein from said end, said upright member received on said first, second and third base support members with said slots respectively receiving said first, second and third base support members, and concealed means in said lower end of said upright rig- 55

idly securing said first, second and third base support members thereto.

6. The pedestal support defined in claim 5 wherein said means is a plurality of welds.

7. The pedestal support defined in claim 5 wherein said upright member is a tubular member.

8. The pedestal support defined in claim 6 wherein said first, second and third support members are fixed to each other by welds concealed in said upright.

9. A method of fabricating a support for an item of furniture such as a chair, table or the like comprising the steps of:

rigidly attaching a support member to one side of a second support member in transverse relationship thereto;

placing a post having a hollow lower end with slots extending longitudinally therein over said first and second support members with the support members received in said slots respectively and the post concealing the connection between the support members; and

bonding said first and second support members to said post at the lower end thereof, said bond wholly confined within said lower end.

10. A method defined in claim 9 wherein the post is attached to said first and second support members by welds located within said lower end of said post to be concealed from view.

11. A pedestal support for an item of furniture such as a chair, table or the like comprising:

a first base support member, a second base support member rigidly fixed to one side of said first base support member and projecting outwardly therefrom in transverse relationship thereto,

an upright vertical support member having a hollow lower end with a plurality of slots extending longitudinally therein from said lower end thereof, said vertical support member received on said first and second base support members with said slots respectively receiving said first and second base support members, and

concealed means confined to said lower end of said vertical support member bonding said first and second support members directly to said vertical support member at the lower end of said vertical support member and wholly confined within said lower end.

12. The pedestal support defined in claim 11 wherein said means are welds.

13. The pedestal support as defined in claim 12 wherein said welds completely fill the lower end of said vertical support member.
